UNITED STATES PATENT OFFICE.

GEORGE W. MASON, OF SHARON, PENNSYLVANIA.

WATER-HEATING APPARATUS.

No. 904,138.

Specification of Letters Patent.

Patented Nov. 17, 1908.

Application filed December 27, 1906. Serial No. 349,742.

To all whom it may concern:

Be it known that I, GEORGE W. MASON, a citizen of the United States, residing at Sharon, in the county of Mercer and State 5 of Pennsylvania, have invented certain new and useful Improvements in Water-Heating Apparatus; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to an improved water heating apparatus for domestic service, and it consists in the certain details of construction and arrangement of the parts, as 20 will be fully described hereinafter.

In the accompanying drawings;—Figure 1 is a side sectional view, partly in elevation, of an ordinary household water heating tank, having arranged in connection therewith, my improved heating apparatus, the same being constructed and arranged in accordance with my invention. Fig. 2 is a sectional plan view of the heating apparatus. Fig. 3 is an enlarged detailed sectional elevation of the heating apparatus, showing the interior water chambers and means of joining the parts together. Fig. 4 is a central sectional elevation of the combination hot and cold water coupling, used in connection 35 with my improved apparatus. Fig. 5 is a sectional plan view of the same, said section being taken on the line $x-x$, of Fig. 4. Fig. 6 is a modified form of the heating apparatus, in which the same is arranged in a horizontal position. Fig. 7 is a sectional end elevation of the same.

To construct an apparatus for heating water for domestic purposes in accordance with my invention, (see Figs. 1 to 5 inclusive) I provide a water tank 1, of suitable form and capacity and arrange the same in a vertical position, the said tank being provided with a water inlet pipe 2, connected with a service pipe, and at the top with a hot water outlet pipe 24, leading to points or places requiring the use of hot water. Arranged beneath the tank 1 is a heater, which consists of a series of water pipes 3, arranged in the form of a circle, which are 55 connected at the top and bottom to heads 4 and 4' by expanding the ends of the tubes,

in a manner well known in the art. Connected to the top head 4, is a cap or cover 6, which is so formed as to provide an interior chamber 8, the said cap being attached to the 60 head 4 by bolts 5; and a perfect steam tight joint made by an annular flange 12, (slightly tapering to its periphery,) entering a circumferential groove formed on the top of said head 4. 65

Formed at the center of the cap 6 is a threaded opening 7, which engages with a combined hot and cold water connection 15, which is screwed into the bottom of the tank 1. This coupling comprises an annular shell 70 15, externally threaded, to couple with the tank and heater, and having an inner partition to form two passages 16 and 18, the one 16 connecting the heater with a hot water pipe 23 arranged in the interior of the tank 75 1 and extending upward to a point near the top of the same. The other passage 18 of this coupling opens into the tank 1 at a point near the base of the same and terminates in a threaded socket 17, in which a 80 pipe 14 is attached, said pipe extending downward and is coupled to the bottom cap 6' of the heater. This latter cap 6' is attached to the lower head of the heater in the same manner as the cap 6 above by the bolts 85 5', also forming a water chamber 9 communicating with the vertically arranged heating pipes 3. The lower head 4' is formed with a passage 10, annular in form, the cap 6' resting on an external shoulder and held 90 tightly by a jam nut 11, as will be best seen by reference to Fig. 3 of the drawings. Projecting upwards through the passage 10, and located centrally of the heating tubes 3, is a 95 gas burner 22, which comprises a short section of pipe having a series of minute radial perforations for the escape of the fuel gas, which enters said burner from a service pipe 21. Surrounding the heating pipes 3, is a casing 19, having a flaring bottom 20, the 100 said casing being supported on two small rods 25, resting on the bottom head 4', and serves to confine the heat generated by the burner 22.

In operation, the tank 1 is first filled with 105 water from the service pipe 2, the gas ignited at the burner 22, and in a few moments the water commences to circulate. This circulation of the water commences from the chamber 8 above, up through the pipe 23 110 to the top of the tank. The cold water in the bottom of the tank 1, will enter the pas-

sage 18, continuing downward through the pipe 14 and enter the lower water chamber 9, from which point it arises upward through the heating tubes 3, gathering heat during its passage therethrough, and is discharged into the tank at the top of the pipe 23, to be led off through the pipe 24, to points or places requiring the use of hot water. This circulation of the water from the tank 1 to 10 and through the heater, is constant, and owing to the arrangement of the burner 22, and the location of the perforations to direct the flame directly against the thin walls of the copper heating tubes 3, water is heated 15 very quickly and with small consumption of fuel.

At Figs. 6 and 7, of the drawings, I have shown a modified form of my invention, in which the heating tubes 3 are arranged in a 20 horizontal position, the number of said tubes being increased by one at the center, and the burner in this modified form arranged directly beneath the heating tubes. This form of heater is almost analogous with that previously described, the same combination hot and cold water connection 15 being used, and the circulation maintained by the water arising from the lower tubes to those above. This heater is also inclosed within a casing 25 having removable heads 22' and a vent opening 21' at the top, which conducts the waste heat against the bottom of the tank 1.

The advantages of this construction of water heaters are many. It can be operated 30 with oil, gas or gasolene as a fuel. The arrangement of the burner with relation to the heating tubes will greatly reduce the consumption of fuel, and by actual tests with other heaters for the same purpose, 35 show a reduction of fuel expense of about one-half, and will heat a given quantity of water in about the same proportion. The heating tubes may be cleaned by simply removing one or both heads, and the construc-

tion and arrangement of the heater is such 45 that any mechanic of ordinary ability may install the same. The heater is simple, durable and of few parts, and with ordinary care cannot get out of order.

Various other modified forms may be 50 made without departing from the spirit of the invention. Therefore I do not wish to confine myself to the exact constructions, shown and described, but wish to claim all such modified forms, as would come properly 55 within the general scope of the invention.

Having thus described my invention, what I claim, and desire to secure by Letters Patent, is;—

1. In a water heating apparatus, the combination of a tank, an inlet for the tank, an outlet for the tank, a connection for the tank having a plurality of passageways, a pipe within the tank, said pipe being in communication with one of the passageways, 65 a heating means communicating with said passageway, and a pipe connection between a second passageway of the connection for the tank and the heating means, said second passageway communicating with the interior 70 of the tank.

2. In a water heating apparatus, the combination of a tank, an inlet for the tank, an outlet for the tank, a connection for the tank having a plurality of passageways, a heating 75 means in communication with one of the passageways of the connection, and means connecting a second passageway of the connection and the heating means, said second passageway communicating with the interior 80 of the tank.

In testimony whereof, I affix my signature, in presence of two witnesses.

GEORGE W. MASON.
